DISPENSER FOR METAL FOIL, WAX PAPER AND PAPER TOWELING

Terry J. Simpkins, Columbus, Ohio, assignor to Lincoln
Metal Products Corporation, Brooklyn, N.Y.

Filed Oct. 21, 1964, Ser. No. 82,275

Term of patent 14 years

(Cl. D52—2)

FIG. 1

FIG. 2

FIG. 3

FIG. 5

FIG. 4

FIG. 1 is a perspective view of a dispenser for metal foil, wax paper and paper toweling, showing my new design;

FIG. 2 is a front view thereof;

FIG. 3 is a rear view thereof;

FIG. 4 is a top view thereof; and

FIG. 5 is a side view thereof.

I claim:

The ornamental design for a dispenser for metal foil wax paper and paper toweling, substantially as shown.
